BURNISHING TOOL

Thomas L. White and Lorenzo Marchetta,
Youngstown, Ohio

Application November 10, 1939, Serial No. 303,824

3 Claims. (Cl. 12—105)

This invention relates to a burnishing tool.

The principal object of this invention is the provision of a burnishing tool adapted to be used in burnishing the edges of shoe soles in the repairing thereof.

5 A further object of this invention is the provision of a burnishing tool adapted to be positioned upon the threaded end of a rotatable shaft.

A still further object of this invention is the 10 provision of a burnishing tool so formed that the working surfaces thereof may be readily reversed in relative position on the shaft so that various thicknesses of shoe soles may be finished.

A still further object of this invention is the 15 provision of a burnishing tool adapted to shape the edges of soles applied to shoes and simultaneously provide and apply wax or other suitable dressing to the edges of the soles being shaped.

20 The burnishing tool shown and described herein has been designed to form a practical and convenient means of shaping the edges of soles and half-soles applied in the process of shoe repairing. It is highly desirable that the shoe repair job be given a thoroughly attractive finish, especially the edges of the soles and for this purpose the tool having multiple burnishing surfaces has been provided. As the tool is used, the alternate 25 burnishing surfaces are utilized depending upon the thickness of the sole, the edges of which are being finished and thus means are provided to readily reverse the burnishing portion of the tool so that the correct burnishing area is at the outermost end of the shaft upon which the tool 30 is positioned.

With the foregoing and other objects in view which will appear as the description proceeds, the invention resides in the combination and arrangement of parts and in the details of construction hereinafter described and claimed, it being understood that changes in the precise embodiment of the invention herein disclosed, 40 can be made within the scope of what is claimed without departing from the spirit of the invention.

The invention is illustrated in the accompanying drawing, wherein:

Figure 1 is a side elevation with parts in cross section showing the burnishing tool and its component parts positioned upon the threaded end of a rotatable shaft.

Figure 2 is an end elevation of the burnishing tool.

By referring to the drawing and Figure 1 in particular, it will be seen that the burnishing

5 tool comprises a sleeve 1 having an inner threaded surface 2 adapted to be threaded upon the threaded outer end of a rotatable shaft 3. This threaded sleeve 1 is preferably positioned upon a section of threaded shaft of approximately the same size as the sleeve so that the threaded sleeve may be turned on to the said threaded shaft tightly so as to remain there securely. The outer surface of the said threaded sleeve 1 is provided with a plurality of annular 10 threads 4 which are adapted to receive in a threadable manner a pin 5 positioned in the 15 burnisher 6. The burnisher 6 is provided on its outermost surface with two separate and distinct burnishing sections 7 and 8 each of which 20 comprises a pair of annular grooves 9 and a centrally positioned burnishing surface 10; each burnishing surface being provided with a plurality of crosswise positioned notches 11. The crosswise positioned notches 11 are provided for 25 the purpose of enabling the burnishing surface of the tool to act more efficiently and to carry wax which will obviously be forced into the shaped edges of the shoe sole as the burnishing process continues, thus leaving an effectively 30 shaped sole edge.

As the tool is adapted to shape the edges of two different thicknesses of soles, it is necessary that means be provided for removing the burnishing surfaced portion of the tool and reverse 35 it in relation to the shaft 3. This is accomplished by simply unthreading it, the pin 5 following the annular threads 4 in the surface of the sleeve 1 thereby permitting the burnishing surface portion 6 of the tool to be removed from the sleeve 30 portion 1. It can then readily be reversed and reapplied to the threaded sleeve 1; the pin again following the annular threads 4 and serving to 40 efficiently position the burnishing surface portion 6 of the tool on the rotatable shaft.

By referring to Figure 2 of the drawing an end elevation of the burnishing tool will be seen; like numerals indicating like parts in relation to Figure 1 of the drawing.

What we claim is:

1. A burnishing tool adapted for use upon a rotatable shaft of a shoe repair finishing machine and comprising a threaded sleeve adapted to be threaded on the said shaft; a burnishing portion threadably mounted upon the said threaded sleeve; a plurality of burnishing surfaces formed on the said burnishing portion of the device so as to enable it to be used to burnish the edges of soles of shoes.

2. A burnishing tool adapted for positioning

upon the threaded end of a rotatable shaft and comprising a threaded sleeve adapted to engage the said threaded shaft; the said threaded sleeve being provided with an outer threaded surface 5 upon which a burnishing portion in the form of a secondary sleeve can be readily positioned and removed; two burnishing areas on the said outer burnishing portion, each of the said burnishing areas comprising a pair of annular grooves and 10 a centrally positioned burnishing surface provided with a plurality of crosswise grooves.

3. A burnishing tool for shoe repair finishing machines adapted to burnish the edges of soles

and apply wax treatment thereto comprising a sleeve adapted to be positioned upon a rotatable shaft; threads formed in its outer surface adapted to readily receive a secondary sleeve; a pair of annular burnishing sections formed on the outer surface of the said secondary sleeve, each of the said annular burnishing sections being of varying widths to provide for burnishing of varying widths of soles of shoes; a pin positioned in the said secondary sleeve and adapted to engage the 10 threads formed on the said sleeve.
